(57) **CLAIM**

The ornamental design for a therapy patch controller, as shown and described.

DESCRIPTION

FIG. 1 is a top perspective view of a therapy patch controller, showing our new design;

FIG. 2 is a bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a top perspective view of the therapy patch controller of FIG. 1, shown in a first condition of use for clarity of disclosure;

FIG. 10 is a top perspective view of the therapy patch controller of FIG. 1, shown in a second condition of use for clarity of disclosure; and,

FIG. 11 is a top plan view of the therapy patch controller of FIG. 1, shown in a third configuration of use on a human face.

In the drawings, the equal-length broken lines depict portions of the therapy patch controller and form no part of the claimed design. The broken lines showing of a patch and human face in FIGS. 9, 10 and 11 depict environmental structure and form no part of the claimed design. All broken lines form no part of the claim.
